Augustus B. Stoughton.
ATTORNEY.

UNITED STATES PATENT OFFICE.

WILLIAM F. H. BRAUN, OF PHILADELPHIA, PENNSYLVANIA, ASSIGNOR TO THE BRAUN COMPANY, OF PHILADELPHIA, PENNSYLVANIA, A CORPORATION OF PENNSYLVANIA.

SLICING-MACHINE.

1,397,158.

Specification of Letters Patent.

Patented Nov. 15, 1921.

Application filed March 2, 1921. Serial No. 448,981.

To all whom it may concern:

Be it known that I, WILLIAM F. H. BRAUN, a citizen of the United States, residing at Philadelphia, in the county of Philadelphia 5 and State of Pennsylvania, have invented certain new and useful Improvements in Slicing-Machines, of which the following is a specification.

The principal object of the present invention is to provide simple, efficient and reliable mechanism for feeding the meat table only at times when the carriage which carries the meat table is at a part of its stroke remote from the knife, so that the 15 meat will be fed into cutting position only when it is clear of the knife and between the slicing operations.

To this and other ends hereinafter set forth the invention comprises the improvements to be presently described and finally claimed.

In the accompanying drawings, forming part hereof, there is illustrated an embodiment of the invention selected from other 25 embodiments for the sake of description, and

Figure 1 is an inverted plan of so much of a meat slicer as is necessary for an understanding of the invention, and

Fig. 2 is a sectional elevation of the same. 30 In the drawings 1 is a carriage and 2 is an oscillating pin by which it is moved back and forth endwise of the machine and on the fixed bed 3, for example, by means of the rotary arm 4 and link 5 pinned to the pin 2. 35 6 is a meat table movable crosswise of the carriage, for example, by means of the screw feed 7, actuated by a pawl 8 and toothed wheel 9. These are usual parts of known slicing machines and need no detail description. 40 10 is an oscillating shaft provided with a radially arranged follower or nut-pin 11, and it is mounted for rotary oscillation in the carriage 1, and by means of a sector-gear 12, this oscillating shaft is geared to the toothed wheel 13, that reciprocates the pawl arm and actuates the screw feed 7 in order to feed the meat table 6. 14 is a traveling nut having a groove or slot 11^a and mounted for endwise reciprocation, but not 45 turning movement on the oscillating shaft 10, and it is reciprocated by a crank arm 15 fast on the pin 2 and having slot-and-pin connection 16 with a bracket 17 provided on it.

55 In the operation of the machine, the pin 2

is oscillated through a portion of a turn by the action of the operating mechanism 4 and 5 in reciprocating the carriage 1 back and forth on the bed 3, toward and away from the knife which is not shown and well understood, and arranged at the top of the sheet although not shown for lack of space and because too well understood to require illustration. The oscillation of the pin 2 turns the arm 15 back and forth in the arc 60 of a circle, thus reciprocating the traveling nut 14 back and forth on the oscillating shaft 10, which latter is turned on its own axis first in one direction and then in the other through a part of a revolution, the 65 pin 11 and spiral thread or groove 11^a co-operating to achieve this result. The speed and timing of the rotation of the oscillating shaft are determined by the pitch and form of the groove 11^a, and the pitch and form of 70 the groove 11^a are such that the pawl and feed mechanism 8 and 7 are properly operated to feed the meat table 6 when the carriage 1 is traveling the portion of its stroke 75 remote from the knife (upper in Fig. 1) end 80 of the machine.

I claim:

1. Feed mechanism for slicing machine meat tables comprising the combination of a traveling carriage, a reciprocatable nut, 85 an oscillatory shaft mounted on the carriage and provided with a nut pin co-operating with the nut, a pawl arm carried by the carriage, and tooth gearing interposed between the pawl arm and shaft, substantially 90 as described.

2. In feed mechanism for slicing machine meat tables the combination of a traveling carriage, a reciprocatable nut and an oscillatory shaft co-operating with the nut and 95 mounted on the carriage, the combination and construction being such that movement of the carriage reciprocates the nut and the reciprocation of the nut oscillates the shaft, substantially as described. 100

3. Feed mechanism for slicing machine meat tables comprising the combination of a carriage, an oscillatory pin by which the carriage is reciprocated, an oscillatory shaft mounted for turning movement in the carriage and provided with a radially arranged nut-pin, a meat table slidable on the carriage and having a feed screw, pawl actuated feed mechanism between the shaft and screw, and a non-rotatable nut slidable on 110

the oscillatory shaft and actuated by the pin and engaging the nut-pin, substantially as described.

4. Feed mechanism for slicing machine meat tables comprising the combination of a carriage and a meat table, an oscillating pin by which the carriage and meat table are reciprocated, mechanism for feeding the table in respect to the carriage, and a traveling nut and oscillatory shaft carried by the carriage and interposed between the pin and feeding mechanism and of which one is reciprocated rectilinearly and the other is oscillated revolvably, substantially as described.

5. Feed mechanism for slicing machine meat tables comprising the combination of a carriage, an oscillating pin by which the carriage is reciprocated and which is provided with a crank arm, an oscillatory shaft mounted for rotary oscillation in the carriage and provided with a radially arranged

nut-pin, a nut engaging the nut-pin and mounted on the oscillatory shaft for endwise reciprocation by said arm, a meat table 25 slidable on the carriage, and pawl driven mechanism carried by the table and operated by the oscillatory shaft for feeding the meat table in respect to the carriage, substantially as described.

6. Feed mechanism for slicing machines comprising the combination of a carriage, means for reciprocating the carriage, a meat table and its feed mechanism mounted on the carriage, a nut and oscillatory shaft 35 mounted on the carriage, provisions interposed between the nut and carriage reciprocating means to cause the nut to travel and oscillate the oscillatory shaft, and connections between the oscillatory shaft and feed mechanism to operate the latter from the former, substantially as described.

WILLIAM F. H. BRAUN.
